US00D997374S

(12) **United States Design Patent** (10) **Patent No.:** **US D997,374 S**
(45) **Date of Patent:** **** Aug. 29, 2023**

(54) **THERAPEUTIC VIBRATION MASSAGER**

(71) Applicant: **Rapid Release Technology, LLC**,
Costa Mesa, CA (US)

(72) Inventor: **Stanley Robert Stanbridge**, Costa
Mesa, CA (US)

(**) Term: **15 Years**

(21) Appl. No.: **29/773,011**

(22) Filed: **Mar. 5, 2021**

Related U.S. Application Data

(63) Continuation-in-part of application No. 17/193,336, filed on Mar. 5, 2021, which is a continuation-in-part of application No. 16/723,135, filed on Dec. 20, 2019, now abandoned, which is a continuation of application No. 15/009,177, filed on Jan. 28, 2016, now Pat. No. 10,548,810.

(57) **CLAIM**

The ornamental design for a vibration therapy device for use as a therapeutic massager, as shown and described.

DESCRIPTION

FIG. 1 is a top, rear, left perspective view of a therapeutic vibration massager, showing my new design;

FIG. 2 is a left side elevation view thereof;

FIG. 3 is a right side elevation view thereof;

FIG. 4 is a front elevation view thereof;

FIG. 5 is a top plan view thereof; and,

FIG. 6 is a bottom plan view thereof.

In the drawings, the broken lines depict portions of the therapeutic vibration massager that form no part of the claimed design.
